(57) **CLAIM**

The ornamental design for a try square with scribe retainer, as shown and described.

DESCRIPTION

FIG. 1 is a front elevational view of a try square with scribe retainer showing my new design.

FIG. 2 is a left side elevational view thereof.

FIG. 3 is a rear elevational view thereof.

FIG. 4 is a right side elevational view thereof.

FIG. 5 is a top elevational view thereof.

FIG. 6 is a bottom elevational view thereof; and,

FIG. 7 is a perspective view thereof.

The broken line showing of a scribe and of fiduciary markings is for illustrative purposes only and forms no part of my claimed design.
